Attest,

UNITED STATES PATENT OFFICE.

EDWARD B. CROY, OF LIMA, OHIO.

DUPLEX FORCE-PUMP.

SPECIFICATION forming part of Letters Patent No. 726,650, dated April 28, 1903.

Application filed July 8, 1902. Serial No. 114,251. (No model.)

To all whom it may concern:

Be it known that I, EDWARD B. CROY, a citizen of the United States, residing at Lima, in the county of Allen and State of Ohio, have 5 invented new and useful Improvements in Duplex Force-Pumps, of which the following is a specification.

This invention relates to a duplex force-pump; and the object of the invention is to provide a simple and effective device of this kind which is light, yet thoroughly strong, and capable of manufacture at a low cost.

The improved pump includes in its construction a base having a plurality of chambers, one of which is intermediate the others and is connected thereto by ports, casings for plungers connected with said base, and a peculiar form of duplex valve in the intermediate chamber, to which intermediate 15 chamber the discharge-pipe of the pump is connected. The duplex valve consists of a sheet or piece of leather or equivalent flexible material secured centrally in place by a plate or the like and the free portions of which 20 constitute valves for said ports.

Other objects and advantages of the invention will be set forth in the following description, while the novelty thereof will constitute the basis of the claims succeeding such 30 description, and said invention is clearly illustrated in the accompanying drawings, forming a part of this specification, and in which—

Figure 1 is a sectional front elevation of a 35 duplex force-pump including my invention. Fig. 2 is a side elevation of the same. Fig. 3 is a sectional plan view of the base of the pump.

Like characters refer to like parts in all the 40 figures of the drawings.

Referring to the drawings, the numeral 1 indicates the base of my improved pump, and it may be made from any suitable material. For example, it may consist of a casting suit- 45 ably galvanized. The base 1 contains the side chambers 2 and an intermediate chamber 3, the said side chambers having inlets 4, controlled by the flap-valves 5 of some suitable construction. The chambered base, 50 which is adapted to be mounted in a well or cistern for effecting the discharge of water therefrom, rests upon the bed or block 5^a of

wood, the parts being suitably united, for example, as follows: The opposite sides of said base have depending lugs or ears 6, countersunk into notches in the upper opposite ends of the block or bed 5^a and secured thereto by screws or the like. In the upper side of the block 5^a are formed the semicircular channels 7, adapted to register with and situated below the inlets 4. It will be understood that the channels 7 extend entirely across the block 5^a, so that water can enter the same from the well or cistern and enter the inlets 4, and consequently the chambers 2 of the 65 chambered or hollow base 1. The walls between the intermediate chamber 3 and the outer chambers 2 have ports 8, vertically disposed, and controlled by a duplex valve hereinafter more particularly described. 70

The cylinders or barrels 9, which are vertically disposed, are screw-threaded or otherwise fitted into openings in the upper side of the base 1, so as to communicate with the respective chambers 2 therein, and may be 75 made of any suitable material—for example, brass tubing. These cylinders or barrels contain pistons or plungers 10, from which the rods 11 extend upward, said rods being united at their upper ends to swivels 12, connected 80 also with the ends of the parallel rocking levers 13, fulcrumed at their centers to a sleeve 13^a, which unites the lowermost sections of the discharge-pipe 14. Said discharge-pipe, which is of small diameter, is 85 tapped into a bushing 20, threaded into the base 1, substantially centrally thereof, and it may be made of any suitable kind of metal, preferably galvanized. The swivel 12 on the right is united to the connecting-rod 15, 90 jointed at its upper end to an actuating-lever, (not shown,) by which the levers 13 can be rocked to reciprocate the stems 11, and consequently the plungers 10, to cause the elevation of the water. 95

The numeral 16 denotes a sheet of flexible material of some suitable kind, such as leather, secured centrally, as by means of a plate 17, to the bottom of the intermediate chamber 3, which, it will be seen, is in direct 100 communication with the discharge-pipe 14. The ends 18 of this sheet of leather or equivalent material 16 are free and extend normally upward in a transverse direction from

the bottom of the base and constitute valves for the discharge-ports 8. In order to insert the valve-sheet 16 into the base 1, I remove the bushing 20, which closes a relatively large opening in said base, and through which opening said valve-sheet and its plate can be readily passed. The width of the plate 17 is a trifle less than the space between the side walls of the chamber 3, and said plate fits flatwise against the upper side of the sheet 16, so as to leave the ends of said sheet free. To hold the plate, and consequently the sheet, in place, I pass the bolt 21 through registering perforations therein, the end of said bolt being adapted to receive a nut, and thereby hold the several parts in proper relation, and the head of the bolt being adapted to fit in a concavity or depression in the upper side of the block or bed 5.
To assemble the parts, the bushing 20 will be first removed, and the sheet of material 16, the free portions 18 of which are to constitute the valves for controlling the ports 8, will be passed through the opening closed by said bushing, and the valve and plate will then be put into place, after which the bolt 21 will be passed through the registering perforations in said parts. The free portions 18 of the sheet will then close the discharge-ports 8. Upon the elevation of either plunger 10 the inlet-valve below the same will be opened, so as to admit a supply of water into the chamber 2 below the same, and when said plunger is depressed said inlet-valve will be closed and the water in said chamber will be forced through the port 8 and up the dis-

charge-pipe 14, the valve 18 being opened by the outflowing water.

Having described the invention, what I claim is—

In a pump of the class described, a base having a plurality of chambers one of which is intermediate the others and is connected therewith by ports, the intermediate chamber having an enlarged outlet in its upper side, a bushing threaded into said outlet, a discharge-pipe threaded into said bushing, barrels containing plungers, connected with said outer chambers, said outer chambers having inlet-ports provided with valves, a block upon which said base is mounted, having transverse channels in its upper side in registration with said inlet-ports, a sheet of flexible material fitted against the bottom of the intermediate chamber, a plate bearing flatwise against said sheet of material centrally thereof, the ends of said sheet being free and constituting valves for said first-mentioned ports, and the said outlet being of a size to freely receive said plate, whereby the plate can be inserted through the outlet into the intermediate chamber, and a bolt passing through the plate, sheet, and bottom of the base, the head of the bolt being fitted in a concavity in the upper side of said block.

In testimony whereof I have hereunto set my hand in presence of two subscribing witnesses.

EDWARD B. CROY.
